Inventor:
Karl Arnstein

UNITED STATES PATENT OFFICE.

KARL ARNSTEIN, OF FRIEDRICHSHAFEN, GERMANY, ASSIGNOR TO THE FIRM LUFT-SCHIFFBAU ZEPPELIN G. M. B. H., OF FRIEDRICHSHAFEN, GERMANY.

RIGID FRAME FOR AIRSHIPS.

Application filed September 3, 1921. Serial No. 498,487.

To all whom it may concern:

Be it known that I, KARL ARNSTEIN, a citizen of the German Republic, residing at Friedrichshafen, a. B., Germany, have invented certain new and useful Improvements in Rigid Frames for Airships (for which I have filed application in Germany March 4, 1920), of which the following is a specification.

- 10 My invention refers to airships of the rigid type and more especially to the rigid structure surrounding the gas cells. Its particular object is to improve and strengthen this structure.
- 15 The load transmitting partitions of the rigid airships consist of ring-shaped polygonal frames whose corners are interconnected by wires. The length of a side of the polygon is limited by the admissible distance of the longitudinal members between which the skin is stayed. As this admissible free span of the skin is very short in relation to the diameter of the ship, specially with larger ships, a great number of sides 20 are required. As further, in the construction of known type, a staying of all the corners was necessary there were produced considerable initial tensions and a system which is statically very sensitive so that—
- 25 especially with larger airships—inappropriately thick rings were required.

These inconveniences are avoided according to this invention by reducing at will the number of the corner-points to be stayed in uniting several sides of the polygon to form a truss without increasing the free span of the skin as between the stayed corners in which the main longitudinal girders are situated any required number of unstayed 30 polygon corners of auxiliary longitudinal girders can be used as supporting points.

It is advisable to include, at the lower half of the airship, in the framework-shaped construction of the ring parts the gangway stanchions in order to withstand better the compressive forces which act from the outside upon the skin at the lower part of the airship and further to compensate the stress on the excessively loaded rings.

50 In order that the invention may be clearly understood, I shall proceed to describe the

same with reference to the form of construction diagrammatically shown in the accompanying drawing, wherein:—

Fig. 1 is a cross section of a rigid frame 55 for an airship,

Fig. 2 is the corresponding side elevation showing a part of the airship formed by two rings and the appertaining longitudinal girders.

Referring to Fig. 1 the stayed main points of intersection are designated by *a*, and the intermediary points of intersection by *b*, in which the longitudinal girders *c* are supported which serve to form the shape, 65 *d* are the gangway stanchions which are connected with the lower ring parts by means of props *e*, *f* are the staying wires which connect the main points of intersection in the plane of the ring.

In Fig. 2 the main longitudinal girders are designated by *g*, the intermediary longitudinal girders by *c*. The wires or cables *h* are conducted over the intermediary girders *c* and serve as diagonal bracing for 75 the panes formed by the stayed ring parts and the main longitudinal girders.

I wish it to be understood that I do not desire to be limited to the exact details of construction shown and described, for obvious modifications will occur to a person skilled in the art.

I claim:—

1. Rigid airship structure comprising longitudinal girders and transverse polygonal frames interconnected by said longitudinal girders, groups of more than two adjacent corners of each frame being stayed to form a substantially symmetrical panel truss having its end points in common with adjacent 80 trusses, and diagonal bracing members interconnecting such common end points.

2. Rigid airship structure comprising longitudinal girders and transverse polygonal frames interconnected by said longitudinal girders, groups of more than two adjacent corners of each frame being stayed to form a substantially symmetrical panel truss having its end points in common with adjacent 95 trusses, a gangway structure between two 100 such trusses, means for bracing such gangway against said two trusses and diagonal

bracing members interconnecting the common end points between the trusses and the top of said gangway structure.

3. Rigid airship structure comprising longitudinal girders and transverse polygonal frames interconnected by said longitudinal girders, groups of more than two adjacent corners of each frame being stayed to form a substantially symmetrical panel truss having its end points in common with adjacent trusses, a substantially triangular gangway structure between two such trusses, means for bracing such gangway against said two trusses and diagonal bracing members interconnecting the common end points between the trusses and the top of said gangway structure.

4. Rigid airship structure comprising longitudinal girders and transverse polygonal frames interconnected by said longitudinal girders, groups of more than two adjacent corners of each frame being stayed to form a substantially symmetrical panel truss having its end points in common with adjacent trusses, said longitudinal girders extending

through all the outside corners of said frames and diagonal bracing members interconnecting such common end points.

5. Rigid airship structure comprising longitudinal girders and transverse polygonal frames interconnected by said longitudinal girders, groups of more than two adjacent corners of each frame being stayed to form a substantially symmetrical panel truss having its end points in common with adjacent trusses, diagonal bracing members interconnecting such common end points and circumferential diagonal bracing members extending from the point of intersection of one longitudinal girder with one frame to the point of intersection of another longitudinal girder with another frame and across intervening longitudinal girders.

In testimony whereof I affix my signature in presence of two witnesses.

KARL ARNSTEIN.
